UNITED STATES PATENT OFFICE.

FRANK W. BLACK, OF DOWNS, KANSAS.

TOOL.

1,220,937.

Specification of Letters Patent. Patented Mar. 27, 1917.

Application filed September 30, 1916. Serial No. 123,144.

To all whom it may concern:

Be it known that I, FRANK W. BLACK, a citizen of the United States, residing at Downs, in the county of Osborne and State 5 of Kansas, have invented new and useful Improvements in Tools, of which the following is a specification.

This invention relates to improvements in means for holding a nut or bolt and engaging 10 with either the nut or the bolt whereby the nut and bolt may be threadedly connected or disassociated and the object of the invention is to produce a device of this character which shall embody the desirable features of cheapness, simplicity and thorough 15 efficiency.

With the above and other objects in view the improvement resides in the construction, combination and arrangement of parts set 20 forth in the following specification and falling within the scope of the appended claims.

In the drawing:

Figure 1 is a view illustrating the operation of the improvement, and

Fig. 2 is a side elevation of the improvement upon a greatly enlarged scale showing the chuck and jaw members thereof in section and engaging respectively with the nut and bolt.

The improvement is primarily devised for applying the nuts and bolts to the meeting flanges of an engine casing, and is thus illustrated in Fig. 1 of the drawings, but it is to be understood that the improvement is not 35 thus to be restricted in its useful capacity, as the same may be employed with equal efficiency upon other structures.

The improvement contemplates the employment of a brace member 1 which has the 40 outer arm of its sweep 2 provided with the usual head 3 which is revolvable upon the said arm of the sweep. The second arm of the sweep, indicated for distinction by the numeral 4, is in a line with the shorter arm 45 5 upon which the head 3 is arranged and the end of the arm 4 is provided with a chuck or socket 5'. It is, of course, to be understood that the chuck or socket 5' may be associated with the arm 4 in such a manner 50 as to permit of the ratcheting of the device should the same be found desirable.

The numeral 6 designates the socket provided upon what I will term the movable jaw 7 of the device. The jaw includes an 55 arm or shank 8 arranged angularly of the jaw 7 disposed parallel with the arm 4 of

the brace 1. The end of the member 8 is offset or turned angularly in the direction of the jaw 7, as indicated by the numeral 9, and this offset or angular end is provided 60 with an opening 10 to receive the arm 4, while the numeral 11 designates a helical spring which is disposed upon the arm 4 and exerts a pressure between the angular end 9 of the jaw 7 and the enlarged chuck 65 5' of the arm 4. By this arrangement it will be noted that the jaw 7 is normally forced toward the chuck end of the arm 4, and in operation the head of a bolt, or if desired, a nut, is placed in the socket 6 of 70 the jaw 7, while the element to be screwed upon the member arranged within the said socket is arranged within the socket of the chuck 5'. The head of the bolt may be received within the socket 6 and the jaw 75 moved longitudinally and outwardly of the arm 4 of the brace 1 to permit of the shank of the bolt being passed through the openings in the plates to be connected. The nut is received in the socket of the chuck 5' and 80 the arm for the said brace is permitted to move in the direction of the bolt. When the bore of the nut is in a line with the threaded shank of the bolt, the brace is rotated by turning the sweep 2 thereof and by this 85 means it will be noted that the nut can be easily and quickly screwed upon the bolt, while the bolt is properly held to receive the said nut. In order to facilitate the operation of the device I provide the arm 8 of the 90 jaw 7 with an outwardly extending handle 12.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what 100 I claim is:

1. In a tool for the purpose set forth, a brace member including a sweep provided with a chuck, a substantially U-shaped member having one of its arms loosely connected 105 with the brace, a spring between the said arm and the chuck of the brace, the second offset arm of the U-shaped member having a socket disposed opposite the chuck, and a handle for the said U-shaped member. 110

2. In a tool for the purpose set forth, a brace including a sweep which has arms in

alinement one of which is of a greater length than the other, a revolute head upon the shorter arm, a chuck upon the end of the longer arm, a jaw having a socket disposed 5 in a line with the chuck, said jaw including an angular arm arranged parallel with the longer arm of the brace, the arm of the jaw having its end offset and provided with an

opening to receive the longer arm of the brace, and spring means between the said 10 offset end of the arm of the jaw and the chuck of the longer arm of the brace for normally forcing the jaw toward the chuck, and a handle for the arm of the jaw.

In testimony whereof I affix my signature. 15
FRANK W. BLACK.
